UNITED STATES PATENT OFFICE

2,479,230

TORQUE MEASURING TOOL

Clement E. Gossling, Toronto, Ontario, Canada

Application September 15, 1945, Serial No. 616,573

5 Claims. (Cl. 73—139)

1

The present invention relates to improvements in tools for applying a turning force to bolts, nuts, screws or other pieces of mechanism where it is desired to accurately apply a desired torsional loading so that the piece being tightened will not be subjected to undesirable or injurious stress and the principal object of the invention is to provide an extremely simple form of tool which may be universally applied to various uses and will be free of delicate mechanisms which may become distorted and inaccurate through use and abnormal conditions.

A further and important object is to devise a construction of tool which will enable its being produced in quantity at relatively low cost, thereby enabling a much wider range of use than tools having delicate mechanisms liable to get out of order.

The principal feature of the invention consists in the novel arrangement of a torsion member fixed at one end in the tool handle and connected at the other end to the load applying element and registering with fixed gauge markings arranged longitudinally of the handle structure to indicate the torque applied through the torsional deflection of said torsion member.

In the accompanying drawings

Figure 1 is a plan view of my improved tool.

Figure 2 is a longitudinal mid-sectional view of the tool taken on the line 2—2 of Figure 1.

Figure 3 is a plan section taken through the line 3—3 of Figure 2 and illustrating the deflection of the longitudinal torsion member.

Numerous forms of torsion wrenches have been devised for the purpose of obviating the application of torsional force to the work piece which would overstrain or injure the same. Such devices have employed a resilient yielding means between the load applying member and the portion engaging the work piece and in these devices various forms of indicators have been arranged, either connected with the work engaging member or the resilient member, to indicate the extent of the torsional load applied.

In the present invention it is proposed to utilize the resilient load applying member directly as the load indicating means.

In the construction herein shown a tubular handle member 1 having an enlarged end 2 is threaded into a cylindrical portion 3 of a hollow head 4.

Mounted within the head 4 in angular relation to the handle 1 is a bushing 5 in which is journaled a spindle 6, the outer end of which, projecting beyond the head, is fashioned to carry a

2

suitable work engaging tool, such as a socket wrench or screw driver bit.

The inner end of the spindle 6 has formed thereon or rigidly secured thereto a bevel gear quadrant 7 which is shown as having its upper face engaging a bearing surface 8 of a cap 9 threaded in a threaded orifice in the top of the head 4.

A bushing 10 is mounted in the end of the tubular handle member extending into the head 4. A bevel pinion 11 having a cylindrical stem 12 journalled in the bushing 10 is housed in the hollow head 4 and meshes with the bevel gear quadrant 7 so that any rotative movement of the spindle 6 within its bearing will be imparted to the pinion.

The stem 12 of the pinion 11 is formed with a longitudinal and axial slot 13.

A torsion member 14, here shown as a flat strip of material, the dimensions and characteristics of which will be suitably proportioned to the desired loading of the tool, has one end inserted in the slot 13 of the pinion stem and said strip extends longitudinally within the tubular handle and has its outer end housed in an axial longitudinal slot 15 in a headed cylindrical member 16 rigidly secured in the outer end of the handle by a cross pin 17.

The tubular handle 1 is provided with a narrow longitudinal slot or slots 18 which is parallel with one longitudinal edge of the torsion member 14 and suitable gauge marks 19 are arranged on the outer surface of the tube along the edge of the slot.

It will be understood that a row of holes may be substituted for the slots 18.

The upper edge of the torsion member will be suitably plated or coloured to present a contrasting appearance to the colour of the handle tube, the interior wall of which may also be contrastingly coloured as desired so that the relative position of the edge of the torsion member and the edge of the longitudinal slot or holes may be readily observed.

When the tool is unloaded the edge of the torsion strip will be visible and in line throughout the entire length of the slot or row of holes.

Upon the application of a load to the work piece, the turning movement of the tool causes the spindle 6 to turn in its bearing and through the gears 7 and 11 such movement will be imparted to the torsion member 14 and as its outer end is anchored, such member will be deflected into helicoidal form.

As the torsion member is thus deflected the edge thereof will be moved out of alignment with the

viewing slot or holes 18 and in accordance with the magnitude of the load applied, the helicoidal curve will move the visible edge to register in angular relation to the gauge marks along the slot, thus indicating to the workman using the tool the amount of torsional movement that is being applied to the work.

The torsion member is herein shown as a single flat strip of material but it will be readily understood that two or more such strips may be used or in fact the torsion member may be round or square or any other cross-sectional shape and may be marked with a longitudinal mark to register with the gauge slot when at rest.

The sectional shape of the torsion member and the material used may be selected to suit the condition for which the particular tool is adapted, as also the gauge marks will be varied, so long as the torsion member selected will on the application of torque deflect helicoidally.

Further, it will be understood that the handle need not be of tubular form, so long as a fixed gauge line is provided to extend longitudinally adjacent to the torsion member.

What I claim as my invention is:

1. A torsion tool comprising a handle having a longitudinal gauge line, a torsion member adapted to deflect helicoidally mounted within and secured at one end to said handle and having a gauge line normally parallel to said longitudinal gauge line but intersecting therewith upon deflection of said torsion member to indicate the torsional force applied thereto, and a rotatable work engaging member mounted in said handle and connected with the other end of said torsion member.

2. A torsion tool comprising, a tubular handle having a longitudinal opening therethrough and gauge marks spaced along said opening, a rotatable work member mounted at one end of said handle, a torsion member adapted to deflect helicoidally connected at one end to rotate with said work member and extending longitudinally within said handle and having its edge normally registering with said longitudinal opening but intersecting therewith upon deflection of said torsion member to indicate the torsional force applied thereto, and means fixedly securing the other end of said torsion member to said handle.

3. A torsion tool comprising a tubular handle having a longitudinally aligned opening therethrough, a gear pinion rotatably mounted at one end of said handle, a torsion member non-rotatably connected at one end to said pinion and extending longitudinally within said handle and arranged normally parallel with said open-

ing therein but intersecting therewith upon deflection to indicate the torsional force applied thereto, means fixedly securing the other end of said torsion member to said handle, a torque applying tool spindle rotatably mounted in angular relation to said handle, and a toothed gear mounted on said spindle and meshing with the aforesaid pinion.

4. A torsion tool comprising a hollow head, a work tool spindle journaled in said head, a toothed gear mounted on said spindle within said head, a tubular handle secured to said head in angular relation to said spindle and having longitudinally aligned openings therein, a member rotatably mounted in said handle adjacent to said head, a gear pinion mounted on said rotatable member within said head and meshing with said toothed gear, a torsion member mounted within said handle and non-rotatably connected with said rotatable member connected to said pinion and having its edge normally aligned with the openings in said handle, means arranged at the other end of said tubular handle rigidly securing the other end of said torsion member, and gauging marks arranged along the longitudinal openings in said handle for measuring the helicoidal deflection of said torsion member from its normal aligned position to indicate the torsional force applied thereto.

5. A torsion tool comprising a hollow head, a tubular handle secured in said head and having a longitudinal slot therein, a work applying member rotatably mounted in said head, a member geared to said work applying member and rotatably mounted in the head end of said handle, a torsion member adapted on the application of torque thereto to deflect helicoidally, secured at one end to said rotatable member and extending longitudinally in said handle and having a mark parallel with said tube slot when at rest, and having its other end secured against rotation.

CLEMENT E. GOSSLING.
